CLAIM

The ornamental design for a mounting pole with mounting plate assembly for a mobile device holder, as shown and described.

DESCRIPTION

FIG. 1 is a perspective view thereof from the front top left; FIG. 2 is a perspective view thereof from the front top left; FIG. 3 is an elevational view thereof from the front; FIG. 4 is an elevational view thereof from the rear; FIG. 5 is an elevational view thereof from the left; FIG. 6 is an elevational view thereof from the right; FIG. 7 is a top plan view thereof;

FIG. 8 is a bottom plan view thereof; and,

FIG. 9 is a perspective view thereof from the rear top left. The broken lines in FIG. 1 depict environment for the mounting pole with mounting plate assembly for a mobile device holder, and portions of the mounting pole with mounting plate assembly for a mobile device holder that form no part of the claimed design.

The broken lines in FIGS. 2-8 depict portions of the mounting pole with mounting plate assembly for a mobile device holder that form no part of the claimed design.

1 Claim, 6 Drawing Sheets
